UNITED STATES PATENT OFFICE.

HOWARD W. BEAVER, OF PITTSBURGH, PENNSYLVANIA, ASSIGNOR OF ONE-HALF TO
WELLINGTON H. MILLIGAN, OF CLAIRTON, PENNSYLVANIA.

STAMP MOISTENING AND AFFIXING DEVICE.

1,035,846.

Specification of Letters Patent. Patented Aug. 20, 1912.

Application filed September 28, 1911. Serial No. 651,677.

To all whom it may concern:

Be it known that I, HOWARD W. BEAVER, a citizen of the United States of America, residing at Pittsburgh, in the county of Allegheny and State of Pennsylvania, have invented certain new and useful Improvements in Stamp Moistening and Affixing Devices, of which the following is a specification, reference being had therein to the accompanying drawing.

This invention relates to a stamp moistening and affixing device and has for its object to provide means in a manner as hereinafter set forth to overcome the inconvenience due to the moistening of stamps by the tongue, said means being further capable of positioning the stamp upon and securing it to an envelop.

Further objects of the invention are to provide a stamp moistening and affixing device with means in a manner as hereinafter set forth whereby it can be adjusted so that stamps of different sizes can be moistened and affixed to an envelop without placing one to the inconvenience of moistening the stamps by the tongue.

Further objects of the invention are to provide a stamp moistening and affixing device which is simple in its construction and arrangement, strong, durable, efficient in its use, conveniently used and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views—Figure 1 is a top plan view broken away of the envelop support; Fig. 2 is a section on line 2—2 of Fig. 1; Fig. 3 is a section on line 3—3 of Fig. 1 and further showing the stamp carrier and affixer in full and dotted lines; Fig. 4 is an inverted plan of the stamp carrier and affixer; Fig. 5 is a modified form of suction head forming elements of the stamp carrier and affixer.

Referring to the drawing in detail, the device includes a support formed of a rectangular base plate 7 provided with an end wall 8 and a side wall 9. The walls 8 and 9 form a guide for positioning the envelop which is indicated at 10.

Projecting from and secured to the outer face of the side wall 9 near one end thereof is a receptacle 11 which contains a body of absorbent material 12, preferably a sponge which is damped. The top of the receptacle 11 at each side thereof is provided with a pair of guide pieces 13. The damped absorbent material 12 is utilized for moistening the stamp. The receptacle 11 has secured thereto a hinged cover 14.

The bottom of the receptacle 11 is formed by an extension 15 of the plate 7. The receptacle 11 is provided with an impervious lining 16 which may be of any suitable material. The base plate 7 is also extended, as at 17, to provide the bottom of a stamp receptacle which is formed from a pair of vertically disposed end members 18 seated in the side wall 9 and in a horizontally extending member 19 which opposes the side wall 9. The members 18 and 19 are suitably connected to the extension 17 and form one side of the end walls of the stamp receptacle; the other side wall of said receptacle is formed by the end wall 9, while the extension 17, as before stated, constitutes the bottom of the stamp receptacle. The stamp receptacle includes a hinged cover 20, means such as adjustable partitions mounted in grooves 22 formed in the opposing faces of the member 19 and wall 9 providing compartments in the stamp receptacle, and which furthermore, provides means whereby the length of each compartment can be increased or terminated whereby stamps of varying lengths can be positioned in the stamp receptacle. The stamps are indicated by the reference characters 23.

Arranged over the base plate 7 at one corner thereof is a guide for a combined stamp carrier and affixer which will be presently referred to and said guide is formed from a pair of spaced longitudinally extending members 24, 25 secured to the end wall 8, and a horizontally disposed member 26 which is connected to the inner ends of the members 24, 25 and also to the side wall 9. The member 24 is attached to the

side wall 9. The members 24, 25 and 26 are flush with the end and side walls 8 and 9 but terminate at a point removed from the base plate 7 to form a space 27 into which 5 that corner of the envelop which is to receive the stamp can be positioned. The inner face of the members 24, 25 are grooved, as at 28, for the reception of adjustable partitions 29 to provide openings 10 of various sizes for the passage of the combined stamp carrier and affixer. It will be stated that the guide can be made of any desired length to provide for the affixing 15 of a series of stamps. As shown by way of example, the guide is arranged for the affixing of three stamps, but this number can be increased or diminished if desired. The stamp receptacle can also be of any desired length so as to provide for a series of stamp- 20 compartments. By way of example, three compartments are shown, but it is obvious that the number can be increased if desired.

The combined stamp carrier and affixer 25 includes a vertically disposed hollow tube 31 having a contracted exteriorly threaded upper end 32 to which is attached a depending nipple 33 and a compressible bulb 34. Integral with and projecting laterally from 30 the member 31 is a handle 35 which can be gripped by the operator for manipulating the combined carrier and affixer. Extending into the lower portion of the member 31 is a hollow nipple 36 of a suction head 37. 35 The nipple 36 is cylindrical in contour while the head 37 is rectangular and which is formed with a centrally disposed chamber 38 into which communicates the opening 39. Communicating with and projecting from 40 the chamber 38 at an inclination are two rows of ports 40 and interposed between the ports 40 and communicating with the chamber 38 is a vertically disposed row of ports 41.

45 In Fig. 5 of the drawings, a modified form of suction head is illustrated which is indicated at 42. The head shown in Fig. 5 is of the same shape as that shown in Fig. 4

but of greater length and width and formed with an increased number of ports 43. 50

The bulb 34 is compressed and the head 37 placed into one of the compartments of the stamp receptacle and against the outer face of stamps, after which the bulb is allowed to expand, creating a suction and holding the stamp against the lower face of the suction head. The stamp is then moistened by moving it into contact with the absorbent body 12, after which the carrier and affixer is thrown downwardly by the compression upon the handle 35 whereby the stamp is affixed to the envelop 10. Prior to the connecting of the stamp to the carrier and affixer, the envelop 10 is placed in position. 65

What I claim is:

1. A device for the purpose set forth comprising a support, a stamp moistener carried thereby, a combined stamp carrier and affixer guide connected to the support and beneath which the envelop is positioned, a stamp receptacle secured to the support, means forming a part of said receptacle to provide for stamps of varying lengths, and means forming a part of said guide to provide for suction heads of varying lengths. 75

2. A device for the purpose set forth comprising a support, a stamp moistener connected to and arranged exteriorly of said support, a stamp carrier connected to and arranged exterior of said support, a combined stamp carrier and affixer guide secured to said support and positioned above the bottom thereof thereby providing a space for the positioning of an envelop upon the support below said guide, said receptacle having means to provide for stamps of varying lengths, and said guide having a part thereof providing means for the passage of suction heads of varying lengths. 90

In testimony whereof I affix my signature in the presence of two witnesses.

HOWARD W. BEAVER.
